[57] CLAIM

The ornamental design of a handset telephone, substantially as shown and described.

DESCRIPTION

FIG. 1 is a side view in elevation of one side of the handset telephone showing our new design;

FIG. 2 is a front view in elevation thereof;

FIG. 3 is a side view in elevation of the left end thereof;

FIG. 4 is a side view in elevation of the right end thereof; and

FIG. 5 is a plan view of the bottom side thereof. The side of the instrument opposite that of FIG. 1 is essentially the mirror image of FIG. 1.

FIG. 4

FIG. 2

FIG. 1

FIG. 5

FIG. 3
